UNITED STATES PATENT OFFICE.

CHARLES WARREN CHENEY, OF ATHOL, MASSACHUSETTS.

MOWING-MACHINE.

SPECIFICATION forming part of Letters Patent No. 278,508, dated May 29, 1883.

Application filed March 10, 1882. (No model.)

To all whom it may concern:

Be it known that I, CHARLES WARREN CHENEY, a citizen of the United States, residing at Athol, in the county of Worcester and State of Massachusetts, have invented 5 certain new and useful Improvements in Mowing - Machines; and I do hereby declare the following to be a full, clear, and exact description of the invention, such as will enable others 10 skilled in the art to which it appertains to make and use the same.

My invention relates to certain new and useful improvements in mowing - machines, and more particularly to the class employing two 15 reciprocating cutters moving in opposite directions to co-operate, like shears, in severing the blades of grass.

The object of my invention is to simplify the construction of the several operating parts of 20 the above-described class of machines, while at the same time rendering them more durable and effectual in operation.

The invention therefore consists in novel 25 features of construction and combination and arrangement of parts, all as will be hereinafter fully described, and set forth in the claims here-to annexed.

Referring to the accompanying drawings, Figure 1 is a plan or top view of my improved 30 machine; Fig. 2, a bottom plan; Fig. 3, a vertical transverse section; Fig. 4, a vertical longitudinal section; Fig. 5, a front elevation; Figs. 6, 7, and 8, detail views.

In the drawings, A represents the frame of 35 the machine; B B, the supporting and drive wheels, provided with the usual clutch mechanism for connecting them with the shaft C, which is journaled in bearings or boxes b b, connected or secured to the frame of the machine.

Upon the shaft C is loosely mounted the cam disk or wheel D, adapted to be connected or thrown into gear with said shaft C through the medium of the usual clutch mechanism, e d. The cam disk or wheel D has a double- 45 grooved rim, d', the grooves and projections d' d' on one side of said rim d' alternating with the corresponding grooves and projections on the other side thereof, all as clearly shown in Fig. 1, so that the centers of the grooves on 50 one side of the rim are directly opposite to or on right lines with the centers of the projections on the other side of the rim.

E represents an arm having its forward end passing transversely through the upper end of a vertical shaft, G, which passes down through the front cross-bar, a, of the frame A, said arm being adjustably secured in said shaft by a set-screw, e. The arm E has a rear forked end, F, rigidly secured thereto or formed integral therewith, as shown in Fig. 7, so as to embrace or extend on opposite sides of the grooved rim of the cam-wheel D, the forked ends f f having on their sides recesses f' f', in which are arranged anti-friction rolls f' f', mounted on journals f' f', and adapted to engage with the double-grooved rim of the cam-wheel D. The object of having the arm E adjustably secured in the shaft G is to permit its being drawn forward to replace the anti-friction rolls when worn, or for other purposes that may be deemed expedient in repairing the operating parts of the machine.

To the lower end of the shaft G is rigidly and centrally secured, or formed integral therewith, a transverse bar, g, connected at its ends 75 by links g' g' with the outer ends of oscillating bars H H, journaled to the under side of the frame A, with one bar in advance or in front of the other, as shown in Fig. 2, the fulcra of said bars being one-third of their lengths 80 from their outer ends.

I I represent substantially transverse parallel rods connecting the inner ends of the bars H H with the inner ends of the cutters J J, adapted to work in the usual finger-bar, K, 85 rigidly connected to the forward end of the usual rocking shoe, k.

The above-described arrangement forms a double compound connection between the shaft G and cutters J J, so that an alternating reciprocating movement is given to the cutters 90 that will pass the teeth beyond each other.

L represents the usual lever, connected to the inner end of the finger-bar by a chain, l, for lifting or raising the outer end of the finger-bar. As heretofore employed, an independent lifting-lever has generally been necessary, in order to raise the inner end of the finger-bar and shoe in passing over obstructions. I accomplish the same result through 95 the medium of the lever L and the following-described friction-connection:

M represents a vertical bar loosely or pivotally connected at its lower end to the shoe k,

and which has a free vertical movement between the inner side of the bar a' of the frame A and the guide-plate m , secured thereto. Said bar M is held in a rigid position, when it is necessary to raise only the outer end of the finger-bar, by means of a pivoted lever, N, having its fulcrum on the projecting rear end of the plate n , so arranged that when the longer arm n' of the lever N is pushed forward by the foot of the operator the shorter end of said lever will press against the bar M, and hold it from vertical movement by the frictional contact of the bar with the rear side of the beam a' or plate m , or a shoulder thereon, the lever N being secured in position by engaging the ratchet-bar n^2 .

The shoe k extends rearwardly, forming the push-bar, which is connected in the usual manner to the rear of the frame A by a ball-and-socket joint, and upon said push-bar is mounted a sleeve, O, having an arm, said sleeve being adjustably secured thereon by a set-screw, o. The arm of this sleeve O is connected to the shipper-bar P by a link, o', so that in raising the outer end of the finger-bar the shoe and push-bar will be turned or oscillated, and thereby disconnect the clutch mechanism, which will be again thrown into gear when the finger-bar is lowered by the shoe and push-bar oscillating or turning back to their original position. By the above-described arrangement I am enabled to throw the operating mechanism in and out of gear through the movement of the lifting-lever, which raises the finger-bar, and simultaneously therewith.

The mechanism for raising and lowering the finger-bar and throwing the operating mechanism in and out of gear is applicable to other forms of mowing and reaping machines, and hence I do not desire to limit myself to its use in the class of machines hereinbefore described.

The cam-wheel as constructed in connection with the means for connecting it with the cut-

ters, as before described, while simplifying the construction, is effectual in operation.

45

The operation of the machine is deemed obvious from the foregoing description. The machine being drawn over the surface of a field or plat of grass, movement is communicated through the supporting or drive wheels to the shaft and cam-wheel, and thence to the cutters through the medium of the intermediate connecting mechanism, by which they are reciprocated or vibrated in opposite directions, which causes them to co-operate, like shears, in severing the blades of grass.

Having thus fully described my invention, what I claim as new, and desire to secure by Letters Patent, is—

1. The combination, in a mowing-machine, of the cam-wheel having grooves and projections alternating with each other on opposite sides of its rim, the forked arm E, provided with the anti-friction rollers, the vertical shaft G, transverse bar g , links $g' g'$, pivoted bars H H, parallel transverse rods I I, cutters J J, and finger-bar, substantially as and for the purpose herein shown and described.

2. In a mowing-machine, the combination, with the cutter or cutters and operating mechanism, the finger-bar, lifting-lever, shoe, and push-bar, and the clutch mechanism, of the adjustable sleeve and link o', for connecting the push-bar with said clutch mechanism, whereby in raising the finger-bar through the medium of the lifting-lever the cutter mechanism will be simultaneously thrown out of gear, substantially as and for the purpose specified.

In testimony whereof I affix my signature in presence of two witnesses.

CHARLES WARREN CHENEY.
